UNITED STATES PATENT OFFICE.

LOUIS STEINBERGER, OF JERSEY CITY, NEW JERSEY.

DESIGN FOR A BOTTLE.

Application filed March 28, 1922. Serial No. 1,434. Term of patent 14 years.

To all whom it may concern:

Be it known that I, LOUIS STEINBERGER, a citizen of the United States, residing at Jersey City, in the county of Hudson and State of New Jersey, have invented a new, original, and ornamental Design for a Bottle, of which the following is a specification, reference being had to the accompanying drawing, forming part thereof.

Fig. 1 is an elevational view of one part of the bottle's circumference;

Fig. 2 is a similar view of another part.
I claim:—

The ornamental design for a bottle, as shown.

LOUIS STEINBERGER.

Witnesses:

GEORGE BODLER,
T. SPIORS.
